ELBERT C. LEACH AND ERIC O. HAMREN, OF OSHKOSH, WISCONSIN, ASSIGNORS TO LEACH COMPANY, OF OSHKOSH, WISCONSIN, A CORPORATION OF WISCONSIN

WATER-CONTROLLING APPARATUS FOR CONCRETE MIXERS

Application filed November 8, 1929. Serial No. 405,557.

The present invention pertains to concrete mixers, and has to do particularly with the means employed in such mixers for measuring and introducing the water mixed with each batch.

The purpose of the invention is to provide a novel water tank and valve assembly which is inexpensive to construct, is easy to operate, will accurately measure out any desired quantity of water, completely empties at each operation, and will not bi-pass water from the inlet to the outlet.

While the foregoing statement is indicative in a general way of the nature of the invention, other objects and advantages will be evident upon a full understanding of the construction, arrangement and operation of the new valve.

One form of the invention is presented herein for the purpose of exemplification, but it will of course be appreciated that the invention is susceptible of embodiment in other structurally modified forms coming equally within the scope of the appended claims.

In the accompanying drawings:

Fig. 1 is a front view of the upper portion of a concrete mixer equipped with the improved water tank and valve assembly of the invention;

Fig. 2 is a partially sectioned side view of the parts shown in Fig. 1;

Fig. 3 is a horizontal section through the valve, taken on the line 3-3 of Fig. 2;

Fig. 4 is a side view of the casing for the valve; and

Fig. 5 is a horizontal section through the stem of the float, taken on the line 5-5 of Fig. 2.

The concrete mixer shown in the drawings is of well known construction and includes a mixing drum 10 which is mounted for rotation within an open-work frame 11. A cylindrical water tank 12 is secured to the frame above the drum, and an upwardly opening valve casing 13 is fastened to the bottom of the tank about the edges of an aperture 14 therein.

The valve casing 13 contains an inlet valve 15 which is adapted to move upwardly into fluid-tight engagement with a valve seat 16

formed in a horizontal portion of the casing. The valve 15 is of the disk type and is adapted to reciprocate vertically within a small cylindrical chamber 17 beneath the valve seat, which chamber is closed at its lower end by a screw plug 18. The chamber 17 is of substantially the same inside diameter as the valve 15, and is provided in its side with a port 19 which communicates with a pipe 20. The pipe 20 is adapted to be connected with any available supply of water under pressure.

The inlet valve 15 is attached to the lower end of a long vertically extending rod 21 which passes through the top of the tank 12, and the upper portion of the rod 21 is encased within a tube 22. An air-filled float 23 is concentrically secured to the lower portion of the tube 22 at a point within the tank and is held at any desired height above the valve 15 by a collar 24 on the upper portion of the tube. The collar 24 is anchored to the rod 21 by a set screw 25 which passes through a vertically elongated slot 26 in the tube 22 and enters a positioning recess 27 in the rod. When the screw 25 is turned inwardly, the side of the collar opposite the screw is drawn toward the rod, and the tube is consequently clamped between the collar and the rod. The position of the float 23 may be readily changed with respect to the valve 15 by merely loosening the screw 25 and shifting the tube 22 up or down. The tube is provided with marks 28 which indicate the amount of water which the tank will receive for any particular setting of the collar.

When the water entering the valve casing 13 through the port 19 reaches the level of the float 23 and raises the latter, the rod 21, being rigidly connected with the float through the tube 22 and the collar 24, raises the valve 15 up against the seat 16, thereby shutting off the flow of water into the tank 12.

The valve casing 13 also contains an outlet valve 29 which is adapted to move downwardly into fluid-tight engagement with a valve seat 30 formed in a horizontal portion of the casing. An outlet port 31 is provided in the casing beneath the valve seat 30, and opens into a downwardly extending pipe 32.

which discharges into the drum 10. The valve 29 is pivotally suspended at 33 from an arm 34 which is secured to a sleeve 35. The sleeve 35 is rotatably mounted in a suitably packed bearing in one side of the casing 13 and provides a bearing for a contained shaft 36, which shaft is coupled, exteriorly of the casing, to an operating lever 37 by a ferrule 38. The sleeve 35 is provided, exteriorly of the casing, with an offset arm 39 through which one end of a bolt 40 extends. The other end of the bolt 40 extends through a block 41 which is pivotally mounted on trunnions 42 in a forged arm 43, which arm is secured to the shaft 36. A coil spring 44 is positioned on the bolt between the ends of the arms 39 and 43, and the extent of separation of the ends is limited by the head 45 and nut 46 of the bolt.

20 The rod 21 to which the inlet valve 15 is attached passes through an elongated slot 47 in an arm 48 which is attached to the shaft 36, and is provided, a short distance beneath the arm 48, with an enlargement 49.

25 When the water in the tank 12 is to be discharged into the drum 10, the hand lever 37 is swung by the operator through a small angle in a clockwise direction, which movement causes the arms 34 and 48 to swing upwardly 30 by reason of the tie connection afforded by the bolt 40. During such movement, the arm 48 slides upwardly along the rod 21 without in any way disturbing the closed inlet valve 15, while the arm 34 lifts the outlet valve 39 and permits the water to flow from the tank into the drum through the pipe 32.

After all of the water has been drained from the tank, the hand lever 37 is swung by the operator in the opposite direction. In-40 stead, however, of stopping the hand lever in its original position, in which position the outlet valve 29 becomes fully seated again, the operator swings the hand lever past that position against the yielding resistance of the 45 spring 44 until the arm 48 has moved into engagement with the enlargement 49 on the rod 21 and has shifted such rod downwardly far enough to dislodge the inlet valve 15 from the seat 16, whereupon the hand lever is re-50 leased to assume its original position, the inlet valve moves into its lowermost open position, and the tank fills up with water to the level determined by the setting of the float 23. The cylindrical shaping of the chamber 55 17 and the close fit of the valve 15 therein combine to prevent the valve from being prematurely closed by the force of the in-rush- 55 ing water.

I claim:

60 1. Water-controlling apparatus for a concrete mixer, including a water tank, inlet and outlet valves for controlling the flow of water into and out of the tank, a float in the tank connected with the inlet valve for automatically closing the latter when the water reaches

70 a certain level, and an operating member connected with the valves in such a way as to open the outlet valve without disturbing the inlet valve when moved in one direction and to close the outlet valve and open the inlet valve when moved in another direction, said inlet valve when closed by the float being maintained in closed position by the pressure of the supply water until forced open by movement of the operating member.

75 2. Water-controlling apparatus for a concrete mixer, including a water tank, inlet and outlet valves for controlling the flow of water into and out of the tank, a vertically adjustable float in the tank connected with the inlet valve for automatically closing the latter when the water reaches the level for which the float has been set, means outside of the tank for adjusting the position of the float, and an operating member connected with the valves in such a way as to open the outlet valve without disturbing the inlet valve when moved in one direction and to close the outlet valve and open the inlet valve when moved in another direction.

80 3. Water-controlling apparatus for a concrete mixer, including a water tank, inlet and outlet valves for controlling the flow of water into and out of the tank, means for automatically closing the inlet valve when the water reaches a certain level in the tank, and an operating lever connected with the valves in such a way as to open the outlet valve without disturbing the inlet valve when swung in one direction and to close the outlet valve 95 and open the inlet valve when swung in the opposite direction, said inlet valve when closed by said automatic valve-closing means being maintained in closed position independently of the action thereon of said means until forced open by movement of the operating member.

90 4. Water-controlling apparatus for a concrete mixer, including a water tank, an inlet valve, means for automatically closing the inlet valve when the water reaches a certain level in the tank, an outlet valve, a hand lever for opening and closing the outlet valve, and a connection between the hand lever and the inlet valve for opening the latter with the hand lever after the outlet valve has been closed by the hand lever.

100 5. Water-controlling apparatus for a concrete mixer, including a water tank, an upwardly opening valve casing attached to the bottom of the tank about the edges of an aperture therein, an inlet valve in the casing having an upwardly extending stem, a float 105 adjustably mounted on the stem for automatically closing the inlet valve when the water reaches the level for which the float has been set, a member for opening the inlet valve, an outlet valve in the casing, a hand lever for opening and closing the outlet valve, and a connection between the hand lever and 110

said member for moving the latter to open the inlet valve after the outlet valve has been closed by the hand lever.

6. Water-controlling apparatus for a concrete mixer, including a water tank, an upwardly opening valve casing attached to the bottom of the tank about the edges of an aperture therein, an inlet valve in the casing having an upwardly extending stem, a float adjustably mounted on the stem for automatically closing the inlet valve when the water reaches the level for which the float has been set, an enlargement on the stem of the inlet valve, a member movable into engagement with the enlargement to move the stem and open the inlet valve, an outlet valve in the casing, a hand lever for opening and closing the outlet valve, and a connection between the hand lever and said member for moving the latter to open the inlet valve after the outlet valve has been closed by the hand lever.

In witness whereof we have hereunto subscribed our names.

25 ELBERT C. LEACH.
ERIC O. HAMREN.
